EXHAUST APPARATUS AND HEAD THEREFOR
 Bernard Chauvin, Cedar Grove, N.J., assignor to Westinghouse Electric Corporation, East Pittsburgh, Pa., a corporation of Pennsylvania

Filed Feb. 23, 1961, Ser. No. 91,172
 5 Claims. (Cl. 141—66)

The present invention relates to exhaust machines and, more particularly, to an improved exhaust machine for high pressure electric lamps and discharge devices and to an improved head for such an exhaust machine.

Heretofore, exhaust machines (of the type shown in U.S. Patent No. 2,254,905, issued Sept. 2, 1941, to D. Mullan and in U.S. Patent No. 2,808,857, issued Oct. 8, 1957, to J. B. Yoder) have utilized one sweep (connecting the exhaust head to the rotary exhaust valve) for evacuation of an electric lamp and another sweep (similarly connecting the exhaust head to the rotary exhaust valve) for the gas filling of electric lamps and discharge devices.

However, when the electric lamp is filled with a gas at a pressure above 1500 mm. of mercury, such high pressure lifts the movable portion of the rotary exhaust valve away from the stationary portion of such rotary exhaust valve with resultant fouling of both the exhaust sweeps and gas filling sweeps with ambient air and in some cases with lubricating oil normally disposed between the valve portions. As a result, the exhaust machine must be shut down, disassembled, cleaned and reassembled before normal operation is resumed. This reconditioning operation is both time consuming and expensive from the labor standpoint. Additionally, in the gas filling of high pressure photoflash lamps with oxygen, mixtures of oxygen and the lubricating oil are subject to spontaneous combustion and resultant explosions.

It is the general object of the present invention to avoid and overcome the foregoing and other difficulties of and objections to prior art practices by the provision of an improved exhaust machine which prevents contamination of the evacuating and gas filling means with deleterious ambient air and lubricating oil and which reduces shut down time and maintenance expense.

Another object of the present invention is the provision of an improved exhaust machine for photoflash lamps, which exhaust machine eliminates the formation of mixtures of oxygen and lubricating oil in the evacuating and gas filling means thereby preventing spontaneous combustion of such mixtures.

A further object of the present invention is the provision of an improved head for an exhaust machine, which head prevents evacuation of the gas filling apparatus by the evacuating means of the exhaust machine.

The aforesaid objects of the present invention, and other objects which will become apparent as the description proceeds, are achieved by providing an improved head for an exhaust machine, which head comprises a compression rubber assembly for hermetically securing a hollow member which is to be exhausted, a first conduit means connected to the compression rubber assembly, a second conduit means also connected to the compression rubber assembly, a first operating means disposed adjacent the first conduit means for closing off the first conduit means, a second operating means associated with the second conduit means for shutting off the second conduit means, and locking means operatively disposed adjacent the first operating means and the second operating means for preventing the first operating means and the second operating means from opening the first conduit means and the second conduit means at the same time.

The improved exhaust machine comprises a rotatable 70 turret, the above mentioned head carried by the turret for hermetically securing a hollow member which is to be

2

exhausted, coupling means rotatable with the turret, the first conduit means for connecting the head to the coupling means, valve means rotatable with the turret, and the second conduit means for connecting the head to the 5 valve means.

For a better understanding of the present invention reference should be had to the accompanying drawings, wherein like numerals of reference indicate similar parts throughout the several views and wherein:

10 FIG. 1 is a vertical sectional view along the line I—I of FIG. 2 in the direction of the arrows of an oxygen filling station of an exhaust machine for high pressure photoflash lamps;

15 FIG. 2 is a fragmentary plan view of the oxygen filling station and adjacent stations of the exhaust machine shown in FIG. 1;

FIG. 3 is an enlarged fragmentary vertical sectional view along the line III—III of FIG. 2 in the direction of the arrows;

20 FIG. 4 is a vertical sectional view along the line IV—IV of FIG. 3 in the direction of the arrows;

FIG. 5 is a horizontal sectional view along the line V—V of FIG. 3 in the direction of the arrows and showing the means for pinching off the oxygen line, which 25 oxygen line is in the "open" position;

FIG. 6 is a view similar to FIG. 5 along the line VI—VI of FIG. 3 in the direction of the arrows and showing the means for pinching off the vacuum line, which vacuum line is in the "closed" position;

30 FIG. 7 is a horizontal sectional view along the line VII—VII of FIG. 3 in the direction of the arrows of the means for operating the compression rubber assembly;

FIG. 8 is a perspective view of a movable cam which 35 is part of the means for operating the compression rubber assembly;

FIG. 9 is a development of the stationary cams and the movable cam for the means for operating the compression rubber assembly and showing such movable cam in the "down" position whereby the compression rubber assembly is closed;

40 FIG. 10 is a view similar to FIG. 9 showing the movable cam in the "up" position whereby the compression rubber assembly is opened;

FIG. 11 is a fragmentary enlarged side elevational view (partially in section) of a device for controlling the 45 flow of oxygen into the photoflash lamp;

FIG. 12 is a diagrammatic plan view of the exhaust machine.

Although the principles of the present invention are 50 broadly applicable to the high pressure gas filling of electric lamps and discharge devices, the present invention is particularly adapted for use in conjunction with the high pressure oxygen filling of photoflash lamps and hence it has been so illustrated and will be so described.

55 With specific reference to the form of the present invention illustrated in the drawings, and referring particularly to FIGS. 1 and 2, the reference numeral 10 indicates generally a turret of an exhaust machine, which turret 10 carries fifty-four heads 12, and is rotatable on a standard 14. The duplexed heads 12 are indexable, two heads 60 at a time, through a like-number of stations by a conventional indexing mechanism (not shown, but of the type shown in U.S. Patent No. 2,569,852, issued October 2, 1951, to J. H. Green).

65 At Stations "1" and "2" (FIG. 12) a photoflash lamp 16 (FIG. 1) is loaded into an open compression rubber assembly 18 and such compression rubber assembly 18 is then closed (FIGS. 3 and 4) about an exhaust tubulation 20 of the photoflash lamp 16.

Compression Rubber Assembly

As shown in FIG. 3, each compression rubber assem-

bly 18 has a body 22 which is limitedly vertically reciprocable in a stationary lower cam 24, the stationary lower cam 24 being mounted in the turret 10 and also serving as a bearing for the body 22. This body 22 is provided with a central bore 26 which connects a compression rubber receiving cavity 28 in one end of the body 22 with the interior of a hollow head portion 30 carried by the other end of such body 22. In order to provide means for retaining (and later compressing) a compression rubber 32 in the compression rubber receiving cavity 28, a retaining plate 34 is positioned in the compression rubber receiving cavity 28 by a plug 36, which plug 36 is threadably secured to the lower stationary cam 24.

The means utilized to reciprocate the body 22 between the "down" position (FIG. 3) wherein the compression rubber 32 is compressed about the tubulation 20 of the photoflash lamp 16 and the "up" position (not shown) comprises a movable cam 38 (FIGS. 1, 3, 4 and 7-8) rotatable on a shouldered mid-portion of the body 22 and disposed between the aforementioned lower stationary cam 24 and an upper stationary cam 40. The stationary cams 24 and 40 are maintained in spaced relation to each other by spacers 42 and 44 (FIGS. 3 and 7).

In order to enable the movable cam 38 to reciprocate the body 22, such movable cam 38 (FIGS. 7-10) is provided with three equispaced upper cam surfaces 46u (which each engage a cooperating cam surface 46su on the upper stationary cam 40) and three equispaced lower cam surfaces 46L (which each engage a cooperating cam surface 46SL on the lower stationary cam 24).

After an exhaust tubulation 20 of a photoflash lamp 16 has been inserted through the plug 36 into the compression rubber 32 and an inner guide 48, a spring-biased plunger 50c (FIG. 7) is moved by conventional operating means (not shown) from the dotted-line position shown in FIG. 7 into engagement with a roller 52c on the movable cam 38 thus causing relative rotary movement of the movable cam 38 through a distance "d," FIG. 9 (with respect to the upper stationary cam 40 and lower stationary cam 24), from the position shown in FIG. 10 to the position shown in FIG. 9 with resultant downward movement of the movable cam 38 through a distance "d₁." This downward movement "d₁" of the movable cam 38 and the body 22 carried thereby compresses (and hermetically seals) the compression rubber 32 about the exhaust tubulation 20.

From Stations "3" and "4" (FIG. 12) through Stations "35" and "36" the duplexed heads 12 are exhausted by an evacuating means.

Evacuating Means

As shown in FIG. 4, a first conduit means or flexible vacuum tube 54 is disposed within each head 12 and extends from the head portion 30 of each head 12 to a vacuum line 56. This vacuum line 56 (FIGS. 1 and 2) connects the flexible tube 54 (through a trap 58) to a movable portion 60 of a rotary exhaust valve of the type disclosed in U.S. Patent No. 2,113,798, issued April 12, 1938, to D. Mullan. A line 62 connects a stationary portion 64 of the rotary exhaust valve to a suitable pump (not shown) but of the type shown in U.S. Patent No. 1,623,315, issued April 5, 1927, to J. R. Kinney.

At the end of the dwell of the duplexed heads 12 at Stations "35" and "36," the vacuum tube 54 is closed off within the head 12 (as now described) by a first operating means, such as a vacuum line pinch clamp means.

Vacuum Line Pinch Clamp Means

Referring to FIGS. 3, 4 and 6, this vacuum line pinch clamp means has an operating lever 66 pivoted at 68 and carries an operating roller 70 which is engageable with a pinch clamp lever 72 pivoted at 74 within a cavity 76v in the head 12. Movement of a spring-biased plunger 78c (from the left-hand dotted-line position shown in FIG. 6 into engagement with a roller 80c and to the right-hand dotted-line position shown in FIG. 6) causes the

operating roller 70 to ride along an arcuate surface 82 on the pinch clamp lever 72 to the position shown in FIG. 6 against a stop 83 where the pinch clamp lever 72 has sealed off the vacuum tube 54.

It will be understood that during this movement of the operating roller 70 and pinch clamp lever 72, these moving parts pass through a dead center position (not shown) but defined by the position wherein the center "C₁" (of the pivot 68 for the operating lever 66); the center "C₂" (of the operating roller 70); and the center "C₃" (of a lug 84 on the pinch clamp lever 72) all lie in a straight line. Beyond this dead-center position is the overcenter position, wherein the resistive force induced in the vacuum tube 54 during the pinching off operation locks the lug 84 against the operating roller 70 (and the operating roller 70 against the stop 83) to permit retraction of the plunger 78c at Stations "35" and "36" (FIG. 12) without releasing the pinch-off of tube 54 at this time.

After the duplexed heads 12 (and the photoflash lamps 16 carried thereby) have indexed into Stations "37" and "38" (FIG. 12) and at the beginning of the dwell, a second conduit means, such as a flexible oxygen tube 86 (FIGS. 4, 5 and 6), disposed within each head 12 adjacent the vacuum line 54 (and connected to the head portion 30, FIGS. 3 and 4) is opened by operation of a second operating means, such as an oxygen line pinch clamp means, to permit oxygen filling of the photoflash lamps 16 at a pressure of about 1500 mm. of mercury.

Oxygen Line Pinch Clamp Means

This oxygen line pinch clamp means (FIGS. 4, 5 and 6), which is similar to the vacuum line pinch clamp means, comprises an operating lever 90 (FIG. 5) pivoted at 68 and provided with an operating roller 92 for engagement with an arcuate surface 94 on a pinch clamp lever 96, which pinch clamp lever 96 is pivoted at 98 within a cavity 76 in the head 12.

Movement of a plunger 100 from the solid-line position shown in FIG. 5 into engagement with a roller 102 and to the dotted-line position shown in FIG. 5, causes the operating roller 92 to ride along the arcuate surface 94 on the pinch clamp lever 96 in a counterclockwise direction to the position shown in FIG. 5. During this engagement of the operating roller 92 with the arcuate surface 94, the operating lever 90, the operating roller 92 and a lug 104 on the pinch clamp lever 96 pass through a dead center position defined by the alignment of the center "C₁" (of the pivot 68); the center "C₂" (of the operating roller 92); and the center "C₃" (of the lug 104) along a straight line. Beyond dead center position the resistive force induced in the oxygen line 86 during the pinching off operation aids the plunger 100 in moving operating roller 92 and the operating lever 90 to the position shown in FIG. 5, where the oxygen line 86 is open to permit an oxygen supply means to fill the photoflash lamps 16 with oxygen at a pressure of about 1500 mm. of mercury.

Oxygen Supply Means

As shown in FIG. 4, the oxygen tube 86 connects the head portion 30 to an oxygen line 108 extending to a flow control device 109 (FIG. 11).

The flow control device 109 (FIG. 11) is of the type disclosed in U.S. patent application, Serial No. 55,025, filed September 9, 1960, by J. R. Ardizzone et al., now abandoned, and assigned to the assignee of the present invention. Such flow control device 109 is contained within a flexible connector 112 for joining the oxygen line 108 to an extension 114 of such oxygen line 108 and comprises a hollow metallic sleeve 116 provided with an aperture 118 of predetermined size and a screen 120. The aperture 118 is smaller than any other restrictive orifice in the oxygen supply means thereby permitting adjustment of the oxygen flow with respect to the aperture 118 as the limiting restriction in the oxygen supply means.

This extension 114 of the oxygen line extends to an oxygen manifold 122, which manifold 122 is connected by another line 124 (FIGS. 1 and 2) and suitable connections, to a rotatable coupling 126, such rotatable coupling 126 being operable to contain the high pressure oxygen within the oxygen supply means while still permitting rotation of the line 124, oxygen manifold 122 etc. with the heads 12. This rotatable coupling 126 is mounted on a nipple 128 and is connected by a connector 130 to a stationary oxygen supply pipe 132, which oxygen supply pipe 132 extends axially through the stationary standard 14 of the exhaust machine to an oxygen supply (not shown).

In order to prevent opening of the flexible oxygen tube 86 (FIGS. 4, 5 and 6) while the vacuum tube 54 is open and the resultant formation of explosive mixtures in the evacuating means and attendant waste of oxygen, each head 12 is equipped with a novel safety or locking means (FIGS. 3-6).

Locking Means

This locking means comprises a pin 136 (FIGS. 3, 5 and 6) which is reciprocable in a hole 138 in each head 12 between the cavities 76_v and 76. Such pin 136 is longer than the hole 138 and has a beveled lower end portion 140L for facilitating entry of the lower beveled end portion 140L into a locking aperture 142 in the pinch clamp lever 72 (for vacuum tube 54) when such pinch clamp lever 72 is in the closed position (FIGS. 3, 4 and 6) and the locking aperture 142 is in registry with the pin 136. From a consideration of FIG. 3 it will be understood that while the vacuum line 54 is closed, the pinch clamp lever 96 (for the oxygen tube 86) may be either closed (not shown) or opened (FIGS. 3, 4 and 5).

As indicated in FIG. 12, after indexing of the duplexed heads 12 to Stations "39" and "40" and at the end of the dwell at such stations, a plunger (not shown, but similar to plunger 100) engages a roller 102c (FIGS. 2, 3 and 5) on the operating lever 90 to cause the pinching off of the oxygen tube 86. During the closing movement of the pinch clamp lever 96 a locking aperture 144 in such pinch clamp lever 96 moves into registry with an upper beveled end portion 140u of the pin 136 and also into registry with the locking aperture 142 in the pinch clamp lever 72. The pin 136 is now free either to move upwardly or to remain in the down position shown in FIG. 3 in the hole 138, depending on further movement of either the pinch clamp lever 72 or the pinch clamp lever 96.

At Stations "41" and "42" (FIG. 12) the duplexed heads 12 and the photoflash lamps 16 carried thereby enter apparatus for sealing off the photoflash lamps 16 and of the type shown in U.S. Patent No. 2,940,231, issued June 14, 1960, to B. Chauvin. The exhaust tubulations 20 of the photoflash lamps 16 are preheated at Stations "44", "47"; the two duplexed photoflash lamps 16 are tipped off and discharged at Stations "48" and "49"; and the duplexed heads 12 (with the residual exhaust tubulations still secured therein) leave the sealing off apparatus at Stations "51" and "52."

At Stations "53" and "54," a plunger 50 (FIG. 7) engages a roller 52 on each movable cam 38 and causes movement of the movable cam 38 upwardly a distance "d₁" from the position shown in FIG. 9 to the position shown in FIG. 10 thereby releasing the compression rubber 32 to permit ejection of the residual portion of the exhaust tubulation from the head 12.

It will be recognized by those skilled in the art that the objects of the present invention have been achieved by the provision of an improved exhaust machine which prevents the formation of explosive mixtures of oxygen and lubricating oil in the evacuating and gas-filling means of the exhaust machine thereby preventing the spontaneous combustion of such mixtures. In addition, the improved exhaust machine prevents contamination of the evacuating and gas-filling means with deleterious ambient

air and lubricating oil thereby reducing shut-down time and maintenance expense. Use of the improved head for an exhaust machine prevents evacuation of the gas-filling apparatus of the exhaust means by the evacuating means of such exhaust machine.

Alternatively, it is to be understood by those skilled in the art that the vacuum tube 54 of each head 12 and the above-described associated elements of the evacuating means may be disconnected from the pump (not shown) and connected to a second low pressure gas-supply means for such head 12.

While in accordance with the patent statutes a preferred embodiment of the present invention has been illustrated and described in detail, it is to be particularly understood that the invention is not limited thereto or thereby.

I claim:

1. A head for an exhaust and gas-filling machine, said head comprising:

- (a) a compression rubber assembly for hermetically securing a hollow member to be exhausted and gas filled;
- (b) a first conduit connected to and in communication with said compression rubber assembly;
- (c) a second conduit connected to and in communication with said compression rubber assembly;
- (d) a first operating means disposed adjacent to said first conduit and operable to move into first-conduit-closing position to close off said first conduit, and said first operating means also operable to move into first-conduit-open position to permit said first conduit to open, said first operating means comprising a first pivoted pinch clamp lever and a first actuating roller which is movable to pivot said first pinch clamp lever to close said first conduit, said first roller after pivoting said first pinch clamp lever to first-conduit-closing position locking said first pinch clamp lever in such conduit-closing position, and said first pinch clamp lever when pivoted to first-conduit-open position remaining in such conduit-open position until moved into conduit-closing position by said first actuating roller;
- (e) a second operating means disposed adjacent to said second conduit and operable to move into second-conduit-closing position to close off said second conduit, and said second operating means also operable to move into second-conduit-open position to permit said second conduit to open, said second operating means comprising a second pivoted pinch clamp lever and a second actuating roller which is movable to pivot said second pinch clamp lever to close said second conduit, said second roller after pivoting said second pinch clamp lever to second-conduit-closing position locking said second pinch clamp lever in such conduit-closing position, and said second pinch clamp lever when pivoted to second-conduit-open position remaining in such conduit-open position until moved into conduit-closing position by said second actuating roller; and
- (f) locking means reciprocable between a position of locking engagement with said first operating means when in first-conduit-closing position and a position of locking engagement with said second operating means when in second-conduit-closing position, and the total reciprocation of said locking means limited so that said locking means is always in locking engagement with one of said first operating means and said second operating means.

2. The head as specified in claim 1, wherein said first conduit is flexible and normally remains in an open position, and said second conduit is flexible and normally remains in an open position.

3. In combination with a machine for exhausting and gas-filling a hollow member, said machine having a rotatable turret, and evacuating means and high-pressure-gas

supply means associated with said machine, the improvement which comprises a head carried on said turret, said head comprising:

- (a) a compression rubber assembly for hermetically securing a hollow member to be exhausted and gas filled;
- (b) a first conduit connected to said evacuating means and in communication with said compression rubber assembly;
- (c) a second conduit connected to said high-pressure-gas supply means and in communication with said compression rubber assembly;
- (d) a first operating means disposed adjacent to said first conduit and operable to move into first-conduit-closing position to close off said first conduit, and said first operating means also operable to move into first-conduit-open position to permit said first conduit to open, said first operating means comprising a first pivoted pinch clamp lever and a first actuating roller which is movable to pivot said first pinch clamp lever to close said first conduit, said first roller after pivoting said first pinch clamp lever to first-conduit-closing position locking said first pinch clamp lever in such conduit-closing position, and said first pinch clamp lever when pivoted to first-conduit-open position remaining in such conduit-open position until moved into conduit-closing position by said first actuating roller;
- (e) a second operating means disposed adjacent to said second conduit and operable to move into second-conduit-closing position to close off said second conduit, and said second operating means also operable to move into second-conduit-open position to permit said second conduit to open, said second operating means comprising a second pivoted pinch clamp lever and a second actuating roller which is movable to pivot said second pinch clamp lever to close said second conduit, said second roller after pivoting said second pinch clamp lever to second-conduit-closing position locking said second pinch clamp lever in such conduit-closing position, and said second pinch clamp lever when pivoted to second-conduit-open position remaining in such conduit-open position until moved into conduit-closing position by said second actuating roller; and
- (f) locking means reciprocable between a position of locking engagement with said first operating means when in first-conduit-closing position and a position of locking engagement with said second operating means when in second-conduit-closing position, and the total reciprocation of said locking means limited so that said locking means is always in locking engagement with one of said first operating means and said second operating means.

4. A head for an exhaust and gas-filling machine, said head comprising:

- (a) a compression rubber assembly for hermetically securing a hollow member to be exhausted and gas filled, said compression rubber assembly comprising a body reciprocable in said head, a compression rubber in said body, a first stationary cam means and a second stationary cam means disposed in spaced relationship, movable cam means connecting to said body, and said movable cam means movable with respect to said first stationary cam means and said second stationary cam means to move said body in said head first to compress said compression rubber about the hollow member to be hermetically secured and thereafter to permit said compression rubber to expand to allow the hollow member to be removed from said head;

(b) a first conduit connected to and in communication with said compression rubber assembly;

(c) a second conduit connected to and in communication with said compression rubber assembly;

(d) a first operating means disposed adjacent to said first conduit and operable to move into first-conduit-closing position to close off said first conduit, and said first operating means also operable to move into first-conduit-open position to permit said first conduit to open;

(e) a second operating means disposed adjacent to said second conduit and operable to move into second-conduit-closing position to close off said second conduit, and said second operating means also operable to move into second-conduit-open position to permit said second conduit to open; and

(f) locking means reciprocable between a position of locking engagement with said first operating means when in first-conduit-closing position and a position of locking engagement with said second operating means when in second-conduit-closing position, and the total reciprocation of said locking means limited so that said locking means is always in locking engagement with one of said first operating means and said second operating means.

5. A head for an exhaust and gas-filling machine, said head comprising:

(a) a compression rubber assembly for hermetically securing a hollow member to be exhausted and gas filled;

(b) a first conduit connected to and in communication with said compression rubber assembly;

(c) a second conduit connected to and in communication with said compression rubber assembly;

(d) a first operating means disposed adjacent to said first conduit and operable to move into first-conduit-closing position to close off said first conduit, and said first operating means also operable to move into first-conduit-open position to permit said first conduit to open;

(e) a second operating means disposed adjacent to said second conduit and operable to move into second-conduit-closing position to close off said second conduit, and said second operating means also operable to move into second-conduit-open position to permit said second conduit to open; and

(f) locking means reciprocable between a position of locking engagement with said first operating means when in first-conduit-closing position and a position of locking engagement with said second operating means when in second-conduit-closing position, and the total reciprocation of said locking means limited so that said locking means is always in locking engagement with one of said first operating means and said second operating means,

said locking means comprising a pin having end portions reciprocable between locking engagement with said first operating means when in first-conduit-closing position and locking engagement with said second operating means when in second-conduit-closing position, and the ends of said pin being beveled to facilitate reciprocation of said pin when one of said first operating means and said second operating means is moved out of locking engagement with said pin.
